PILOT CUT-OFF FOR GAS BURNERS

Filed Sept. 16, 1927

UNITED STATES PATENT OFFICE.

ROBERT F. BOGER, OF BOSTON, MASSACHUSETTS, ASSIGNOR TO SPENCER THERMOSTAT COMPANY, OF CAMBRIDGE, MASSACHUSETTS, A CORPORATION OF MASSACHUSETTS.

PILOT CUT-OFF FOR GAS BURNERS.

Application filed September 16, 1927. Serial No. 219,939.

This invention relates to control systems for gas burners and more particularly to a control system including a thermostat located in the high heat zone where the gas is burned and adapted to cut off the flow of gas in the event that the flame is accidentally extinguished.

Heating by gas is now very common for water heaters, stoves, furnaces and certain types of automatic refrigerators and it is customary to vary and in some cases to cut off the heat applied by automatic or manually controlled devices, the burners being often relatively inaccessible. For the purpose of insuring the continuous automatic action of burners of this character, it is customary to provide a pilot to relight the main burner when necessary, although the pilot need not be used if the controlling means is adapted merely to regulate the height of the flame of the main burner. It sometimes happens in this latter case that the flame in the main burner is accidentally extinguished or in the case where a pilot is used and the main burner is intentionally extinguished, the pilot also goes out, so that when the flow of gas to the main burner is reestablished it is not ignited, but escapes to the surrounding parts of the building in which the burner is located with attendant risks to the occupants both from fire and asphyxiation.

Among the objects of the present invention, therefore, are to provide an automatic control or safety device responsive to the temperature of the pilot, if one is used, or to the temperature in the heated zone in which the gas is burned, which will function quickly and in a certain manner to cut off the entire flow of gas both to the main gas burning devices and the pilot, if one is used, in the event that the flame is accidentally extinguished; to provide for relighting the devices without the necessity of first warming the thermostat; to provide in control devices of this character a cut-off valve so located as to be out of the high heat zone of the burner and consequently more durable and less likely to get out of order; and generally to improve devices of this character.

Other objects and advantages of the invention will be apparent from the following specification and appended claims when taken in conjunction with the accompanying drawings, in which:

Fig. 1 is a plan view of the valve, thermostat and pilot; 55

Fig. 2 is a central section taken on the line A—A in Fig. 1 showing the valve open;

Fig. 3 is a section similar to Fig. 2 showing the valve closed; 60

Fig. 4 is a fragmentary section showing the means of mounting the thermostatic disk; and

Fig. 5 is a fragmentary section showing a modified form of manual resetting means for 65 the valve.

The device comprises a valve casing generally indicated at 1 which is here shown as made up of two parts 2 and 3 threaded together at 4, the lower part 2 having a wall 5 70 therein provided with an aperture 6 through which gas may flow from the inlet end 7 to the outlet end 8. The wall 5 is provided with a central aperture 9 in which is mounted the stem 10 of a poppet valve 11 which may be fixed thereto in any suitable manner, as for example by the nut 12 threaded on the valve stem. At its lower end the valve stem 10 is provided with an outwardly extending annular flange 13 on which is seated a helical compression spring 14 extending between this flange and the lower side of a boss 15 which is preferably formed integral with the wall 5 about the valve stem, this spring thus tending to force the valve 11 toward its closed 85 position where the downwardly turned annular flange portion 16 seats upon the upper surface of the wall 5. The lower end of the valve stem 10 is provided with a recess 17 in which is located a ball 18. A cam member 90 19 is fixed to a shaft 20 which extends through a suitable packing in the side of the valve casing 2 and is provided at its outer end with a thumb nut 21 by which the cam 19 may be rotated. The cam 19 is aligned with the valve stem 10 and is adapted to engage the ball 18 so that upon rotation of the cam, the ball and valve stem are forced upwardly to open the valve, as seen in Figs. 2 and 3. I preferably provide a notch 22 in the highest portion of the cam 19 in which the ball 18 may seat in the open position of the valve, whereby to prevent accidental dislodgment from open position. 95

I provide means, including a thermostat, 105 for moving the cam to close the valve when such action is necessary, such means taking the form of a tube 23 threaded into the lower

- portion 2 of the valve casing, as shown at 24, a jam nut 25 being provided if it is desired to hold the tube more firmly to the valve casing. The tube 23 is provided with an enlargement 26 which cooperates with a similar enlargement 27 which may be integral with the pilot member 28, the latter having a suitable opening for the egress of gas to sustain a pilot flame. Enlargements 26 and 27 are provided with suitable interengaging flanges 29, as seen in detail in Fig. 4, and are provided with an annular spacing ring 30 for a purpose later to be described. A bimetallic disk 31 is mounted between the enlargements 26 and 27 with its periphery in heat conducting relation therewith. In order that the disk 31 will not be so tightly gripped between the members 26 and 27 as to prevent its efficient operation the spacer ring 30 is made slightly (e. g. .005 inches) thicker than the disk. The inner diameter of this spacing ring may also be slightly greater than the diameter of the disk 31, as indicated in Fig. 4, to prevent binding.
- The disk 31 is preferably bimetallic, being formed of two component disks welded together, the materials such as iron and brass of the respective disks having different coefficients of expansion. The disk 31 is normally cupped (as by swaging) in such direction that the component part having the higher coefficient of expansion is on the concave side. Consequently upon raising the temperature of the disk the unequal expansion of the materials forming the disk will cause a tendency to flatten the cupped surface until at a predetermined temperature a sudden curving in the opposite direction occurs, which reversal of shape will be maintained until the temperature has been substantially lowered. Thereafter upon reaching a substantially lower temperature, the disk will suddenly return to its initial shape. The materials and thickness of the component parts and the degree of curvature are so chosen that the disk will snap in one direction when heated to the desired temperature (e. g. 120° F.) and will snap back at a lower temperature (e. g. 100° F.). Suitable materials are sheet brass and nickel steel having a thickness of .005 and .005 inches respectively and suitable cupping for a disk $\frac{3}{4}$ inches in diameter is .02 inches.
- It will be understood however that the present invention is not limited to any particular combination of materials having different thermal coefficients of expansion but is intended to embrace in its scope any combination of materials having dissimilar thermal coefficients of expansion sufficient to cause the reversal of curvature. Furthermore, the two materials comprising the composite thermostatic disk may be secured together in any desired manner by riveting, soldering, brazing, or otherwise although it is preferred to unite

the materials comprising the disk by welding or similar means to secure a substantially invisible sheet.

A rod 32 is rigidly fixed to the center of the disk 31 in any suitable manner as by a nut 33 engaging a reduced threaded portion of the rod which protrudes through a central aperture in the disk. The rod 32 extends axially through the tube 23 into the interior of the valve casing and is aligned with the cam 19.

From the above description, the operation of the device will be obvious. Starting with the parts in the position shown in Fig. 2 when the burner and pilot are both lit, the thermostat will be cupped to the right, thus keeping the rod 32 at its right-hand position. If for any reason the pilot and the main burner are extinguished, the thermostat will cool until its critical temperature is reached, at which time it will snap abruptly to the left, as seen in Fig. 3, thus pushing the rod 32 to the left and rotating the cam 19 in a counter-clockwise direction to permit the spring 14 to close the valve. Inasmuch as the gas feed to the pilot is from the outlet side of the valve and thence through the annular space between the tube 23 and the rod 32 and through the perforations 34 in the disk 31, it is obvious that when the valve 11 is closed, not only the main burner, but the pilot as well, will be completely turned off, thus entirely preventing the escape of gas. When it is desired to relight the burner, the thumb screw 21 is rotated to open the valve and the burner is lighted in any suitable manner.

In some places the laws prohibit the use of gland packings in connection with gas devices, so that a manual resetting device such as is shown in Fig. 5 must be resorted to, that is, in which the rod 20 extends through the side of the valve casing 1 and through a suitable boss 35 without the use of packing and is provided with a squared end 36 which may be engaged by any suitable tool, the whole being normally covered by a cap 37 which may be threaded to the outside of the boss 35 as shown at 36.

In some cases the use of a pilot 28 may be dispensed with, in which case the enlargement 27 is merely provided with a closed end and the thermostat may be imperforate. In this event the thermostat is responsive solely to the heat of the main burner, the other parts being exactly the same as in the form above described.

As many changes might be made in the device as shown and described without departing from the spirit of my invention, I do not wish to be limited except by the scope of the appended claims.

I claim:

1. A gas burner control device comprising a gas supply line, a poppet valve therein, resilient means tending to hold said valve

- closed, a cam pivoted to the valve casing and aligned with the valve stem to open the valve, the cam having a notch engageable with the end of the valve stem at the full open position of the valve to prevent accidental closing thereof, a gas pilot having a gas supply tube connected to said valve casing, a bimetallic thermostat disc associated with said pilot, and means connecting said disk with the interior of the valve casing and adapted to rotate said cam to permit the closing of the valve when the disk cools to a predetermined temperature due to the pilot being extinguished.
- 5 2. A gas burner control device comprising a gas supply line, a poppet valve therein, resilient means tending to hold said valve closed, a cam pivoted to the valve casing and aligned with the valve stem to open the valve and hold it open against the action of said resilient means, a gas pilot, means for conducting gas from the outlet side of said valve to said pilot, a thermostat associated with and adapted to be heated by said pilot, means operatively connecting the thermostat with said cam so arranged that when the thermostat cools to a predetermined temperature due to the pilot being extinguished it will move the cam out of line with the valve stem and permit the valve to close under the action of said resilient means, and manual means for resetting the valve to its open position.
- 10 3. A gas burner control device comprising a gas supply line, a poppet valve therein, resilient means tending to hold said valve closed, a cam pivoted to the valve casing and aligned with the valve stem to open the valve and hold it open against the action of said resilient means, a tube mounted in the valve casing and communicating with the outlet side of the valve, the tube having a pilot opening at the end remote from the valve, an enlargement in the tube adjacent to the pilot opening, a snap action thermostat in said enlargement in heat conducting relation with the walls thereof, and a rod rigid with the thermostatic element and extending through said tube to contact with and rotate said cam to permit the valve to close when the thermostat is cooled to a predetermined temperature due to the pilot being extinguished, whereby the valve may be located out of the hot zone in which the gas is burned.
- 15 4. A gas burner control device comprising a gas supply line, a poppet valve therein, resilient means tending to hold said valve closed, a cam pivoted to the valve casing and aligned with the valve stem to open the valve, the cam having a notch engageable with the end of the valve stem at the full open position of the valve to prevent accidental closing thereof, a gas pilot having a gas supply tube connected to the outlet side of said valve casing, a bi-metallic disk thermostat associated with said pilot, a rod extending from said disk to said valve and cooperable with said cam to move the latter and permit said resilient means to close the valve when said disk has cooled to a predetermined temperature.
- 20 5. A gas burner control device comprising a gas supply line, a poppet valve therein, resilient means tending to hold said valve closed, a cam pivoted to the valve casing and aligned with the valve stem to open the valve, the cam having a notch engageable with the end of the valve stem at the full open position of the valve to prevent accidental closing thereof, a gas pilot having a gas supply tube connected to the outlet side of said valve casing, an enlargement in said tube adjacent to said pilot, a perforated bi-metallic disk thermostat in said enlargement with its periphery in heat conducting relation with the walls thereof, a rod rigid with the center of said disk and extending axially through said tube to the interior of said valve casing, the inner end of said rod adapted to engage said cam abruptly and positively to rotate it to permit the valve to be closed by the action of said resilient means when the thermostatic disk has cooled to a predetermined temperature, and manually operable means to reset the cam to open the valve independently of the thermostat, whereby the valve may be located out of the high heat zone where the gas is burned.

Signed by me at Cambridge, Mass., this 14th day of September, 1927.

ROBERT F. BOGER.
